O. GOETZKE.
SAFETY RAZOR AND BLADE.
APPLICATION FILED DEC. 21, 1916.

1,221,004.

Patented Mar. 27, 1917.

UNITED STATES PATENT OFFICE.

OTTO GOETZKE, OF JERSEY CITY, NEW JERSEY.

SAFETY-RAZOR AND BLADE.

1,221,004.

Specification of Letters Patent. Patented Mar. 27, 1917.

Application filed December 21, 1916. Serial No. 138,138.

To all whom it may concern:

Be it known that I, OTTO GOETZKE, a citizen of the United States, and a resident of Jersey City, county of Hudson, and State of New Jersey, have invented certain new and useful Improvements in Safety-Razors and Blades, of which the following is a specification.

My invention relates to safety razors and blades therefor.

In razors constructed in accordance with my invention, the holder and its handle, that is to say, the entire razor, with the exception of the removable and replaceable blades, is permanently connected together in such manner that it may be readily opened and closed for the insertion and removal of the replaceable blades, and the cleaning and drying of the device is easily and conveniently accomplished. With a holder so constructed of articulated parts, the arrangement and manipulation of the parts for the clamping and unclamping of the blade is made extremely simple, and there is no opportunity for any of the parts to be mislaid or lost, as may occur in safety razors in which the various parts of the holder are not permanently connected together.

In the embodiment of my improved razor selected for illustration these desirable results are accomplished by making the rear or bottom part of the holder in two halves and hinging each of the halves to the top portion of the holder at the ends thereof, and providing a handle piece on each of these hinged halves of the under portion of the holder, and detachable means for securing such handle pieces together at the ends thereof remote from the holder head. Such construction, in addition, to affording the advantageous features already referred to, provides a two-piece handle composed of parallel separated members, and I have found that a handle so made up is particularly advantageous in the act of shaving, as it affords a comparatively broad holding means which does not turn readily in the hands, and the thumb of the user rests naturally in the opening between the two parallel handle members. With the handle so constructed there is none of the turning of the razor or of the handle with respect to the razor, which may occur with the ordinary cylindrical handle commonly provided in the safety razors of the hoe type, to the

improvement of which type of safety razor my invention is directed.

Another feature of the invention which is of importance resides in the fact that the parts of the razor, being hinged together at their ends, may readily be rounded off smooth, the hinged construction lending itself naturally to the provision of such rounded ends and affording protection against cutting the flesh with the corners of the blades and scratching the flesh with sharp corners of the holder.

The blade which is preferably used in a razor in accordance with my invention has cutting edges at each side, though blades with a single cutting edge may be used, and such double-edged blade when present is preferably provided with a central stiffening backing which may be utilized to correctly position the blade in the holder, grooves being preferably provided in the holder parts for receiving the backing of the blade and the projection of the cutting edge being determined by the blade being positioned in the holder with its backing in the groove provided therefor, whereby the projection of the blade edge is accurately determined and the blade accurately positioned. The holder may be provided with additional positioning means, if desired, and the blade provided with cut-out parts or otherwise properly formed to receive such positioning means.

As the manufacture of double-edged razor blades having both edges formed on the same piece of steel is attended with considerable practical difficulties, such as the protection of one edge while the other is being formed and the like, I preferably make my improved blade in two parts with but one razor edge on each part, and to form the completed blade I bring the parts together with their unsharpened edges toward one another, the line or region of separation between the two blade parts being covered by the centrally arranged backing members already referred to. Blades of other forms may be used, however.

With the foregoing and related objects in view, my invention consists in the parts, improvements and combinations herein set forth and claimed.

In the accompanying drawing I have illustrated, for the purpose of making my invention clearly understood, a preferred

embodiment thereof and certain modifications. In the said drawing, which forms a part of this specification and in which the same reference numerals are used uniformly 5 to designate the same parts throughout, Figure 1 is a perspective view of a razor embodying my invention with the blade in place and the parts in position for use. Fig. 2 is a central, longitudinal sectional view of 10 the construction shown in Fig. 1. Fig. 3 is a perspective view showing the holder of Fig. 1 opened up and the blade lifted out, and Fig. 4 is a fragmentary perspective view showing a modified form of blade and 15 blade positioning means and with one of the hinge pins of the holder removed and the parts slightly separated.

Reference character 10 is applied to designate the main, top or outer portion of the 20 holder. This principal holder member 10 may be provided with a central longitudinal groove 11. The under or rear holder members 12, 12 are preferably two in number, and each one is preferably about half the 25 length of the principal holder member 10. They preferably carry the guard consisting, in the form shown, of teeth 13, and are hinged to the principal holder member 10 preferably at the ends thereof. In the form 30 shown this hinged construction is obtained by providing the holder portion 10 with rearwardly or backwardly projecting lugs 14, 14 having transverse bores 14', and the said lugs 14 are received between ears 15, 15 35 on the hinge ends of the rear members of the holder, which are likewise provided with transverse perforations 16, and pins 16' are passed through these aligned perforations. With this arrangement the ears 15 on the 40 rear holding members 12, 12 may readily be rounded off as shown, as also the ends of the holder member 10 and the lugs 14 thereon so as to form a holder having smooth rounded ends, which may be used for removing 45 hair from any part of the body without danger of cutting the flesh or bruising or scratching the person, as may happen with razors having sharp corners at the ends and not having sufficient protecting means for 50 the corners of the blade. While other means may be resorted to for clamping the holder parts together, in the form shown each of the parts 12 is provided with a handle member 17 secured thereto preferably near the 55 free end thereof, and these handle members 17, which are preferably made up of cylindrical rods or tubes, are provided at the ends thereof remote from the holder with detachable means for clamping the same together, 60 and in the form shown such detachable clamping means takes the form of a latch 18 mounted to turn freely on one of the handle members 17 and with a notch 19 therein adapted to receive and hold a portion 65 of the remaining handle member 17,

such portion in the form shown being at the end thereof and being reduced somewhat in diameter, as shown at 20, so that when the parts are connected together a smooth construction is afforded free from objectionable protuberances, and the handle members 17 being in use substantially parallel to one another, are conveniently grasped, the thumb of the user resting naturally upon and between them. As will readily be observed, the handle members, when the blade is in place, may have a slight tendency to spring away from one another at their ends, and this springing tendency, together with the holding action of the latch 18, may be relied on to keep the parts in their correct assembled relation when the blade is in the holder and the handle parts clamped together. Other latches and latch holding means may, of course, be utilized if desired. 85 The preferred form of blade comprises two single-edged, similar portions 21 having razor edges 22 and opposite unsharpened edges 23 assembled back to back with their edges 23, 23 toward one another, and with 90 a backing member 24 which may encircle the completed blade at the center thereof and is preferably permanently secured in any desired way to the two blade portions. The blade portions may be notched at their ends, 95 as shown at 25, 25, Fig. 4, leaving notches 26, 26 centrally of each end of the completed blade and with a blade having its ends notched, one of the holder parts, as the holder member 10, may be provided with 100 lugs 27 (Fig. 4) for entering such notches and positioning the blade properly in place. In such case the grooves 11', provided for receiving the backing when a backed blade is used, need not be so accurately formed as 105 must be the case when the lugs 27 are dispensed with and the grooves used with the blade backing to determine the position of the blade in use. When the lugs 27 are provided in the holder member 10 the coacting 110 holder members 12 may be cut away to make room therefor, when the holder is closed up, as shown at 28, Fig. 4.

When a blade, such as shown in Figs. 1 and 2, is placed in the holder, the backing 115 member 24 of the blade rests in the groove 11, thereby determining the extent of projection of the edge with respect to the holder and guard, or with the construction of Fig. 3 the extent of blade projection may be determined by the lugs 27 fitting in the recesses 26. The holder being closed by bringing the handle portions 17, 17 together and latching them, the grooves in the rear holder members, 12, 12 receive and clamp the blade 120 to the holder member 10 by the stiffening backing on the opposite sides of the blade and the entire structure is clamped together as by means of the latch 18, the blade being 125 firmly held in place in the holder by means 130

of its backing 24, the depth of the groove 11 in the holder portion 10 being preferably somewhat less than the thickness of the backing strip 24 in order that the blade may be 5 clamped tightly in place by the back.

It is to be understood that the construction illustrated is for the purpose of affording a clear understanding of my invention only, and that I am not to be confined to 10 the specific form or forms shown and described except as required by my claims, by which the scope of my invention is defined.

Having thus described my invention, I claim:

- 15 1. A safety razor including, in combination, a holding member having lugs centrally arranged at the ends thereof, coöperating holding members pivotally connected to the said holding member, a double-edged blade provided with a backing member and having recesses at each end thereof arranged to receive the said lugs for centering the blade upon the holding member, retaining means for said blade including a 20 groove arranged to receive the said backing member, and means including a pair of coöperating handle members detachably secured together for clamping the blade between the said holding member and the coöperating holding members.
- 25 2. A double-edged blade for safety razors comprising oppositely disposed blade portions each having a single sharpened edge and an opposite unsharpened edge, and a 30 backing member for said blades having an opening therethrough, said unsharpened edges of the blade portions being arranged back to back within the backing member and movable in the opening therein when 35 being clamped in position in the razor.
- 40 3. A double-edged blade for safety razors comprising oppositely disposed blade portions each having a single sharpened edge

and an opposite unsharpened edge having a recess at each end thereof, and a backing 45 member for said blades having an opening therethrough, said unsharpened edges of the blade portions being movable in the said opening when the double-edge blade is clamped in position in the razor and arranged back to back within the backing member to form open ended recesses at each 50 end of the double-edged blade.

4. A safety razor including, in combination, a holding member, coöperating holding members pivotally connected to the said holding member, a double-edged blade provided with a backing member, retaining means for said blade including a groove arranged to receive the said backing member, and means including spaced handle members for positively gripping the razor when in 55 shaving position and for clamping the blade between the holding member and coöperating holding members.

5. A safety razor including, in combination, a holding member, coöperating holding members pivotally connected to the said holding member, a doubled-edged blade provided with a backing member, retaining means for said blade including a groove arranged to receive the said backing member, means including spaced handle members for clamping the blade between the holding member and the coöperating 70 holding members, and means including a latch pivoted to one of the handle members for yieldingly and detachably securing the said handle members together.

In testimony whereof, I have signed this 80 specification at New York city this 13 day of December, 1916.

OTTO GOETZKE.
